Primary Examiner — Susan Hattan*Assistant Examiner* — Brett Miller(74) *Attorney, Agent, or Firm* — Kleinberg & Lerner, LLP;
Marvin H. Kleinberg; Marshall A. Lerner(57) **CLAIM**

The ornamental design for a beverage container, as shown and described.

DESCRIPTION

FIG. 1 is a perspective view of a beverage container showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom plan view thereof.

The broken lines represent portions of the structure that form no part of the claim.
